Primary Examiner — Mojtaba Tehrani(74) *Attorney, Agent, or Firm* — Woodard, Emhardt, Henry, Reeves & Wagner, LLP(57) **CLAIM**

The ornamental design for a firearm accessory, as shown and described.

DESCRIPTION

FIG. 1 is a back, top perspective view of the firearm accessory showing my new design;

FIG. 2 is a front, bottom perspective view thereof;

FIG. 3 is a front view thereof;

FIG. 4 is a back view thereof;

FIG. 5 is a right side view thereof;

FIG. 6 is a left side view thereof;

FIG. 7 is top view thereof; and,

FIG. 8 is a bottom view thereof.

The evenly broken lines depict unclaimed portions of the firearm accessory; The dash-dot-dot broken lines depict symbolic break lines, which disclose indeterminate length. The broken lines form no part of the claimed design. The appearance of any portion of the firearm accessory between the break lines that are not shown, from no part of the claimed design.

1 Claim, 4 Drawing Sheets(56)
